Primary Examiner — T. Chase Nelson*Assistant Examiner* — Kathleen M Sims(74) *Attorney, Agent, or Firm* — Shoemaker and Mattare**CLAIM**

The ornamental design for a cleaning, disinfecting and drying machine, as shown and described.

DESCRIPTION

FIG. 1 is a front elevational view of a cleaning, disinfecting and drying machine, showing our new design;

FIG. 2 is a left side view thereof;

FIG. 3 is a rear elevational view thereof;

FIG. 4 is a right side view thereof;

FIG. 5 is a top plan view thereof;

FIG. 6 is a bottom plan view thereof; and,

FIG. 7 is a perspective view thereof, from the top, front and left side.

The features shown in broken lines form no part of the claimed design.

The broken line showing of details in FIGS. 2, 3, 4, and 6 is included for the purpose of showing environmental portions of the cleaning, disinfecting and drying machine that form no part of the claimed design.
